Christian J. Kaiser,

BY

Geo. P. Kimmel.
ATTORNEY.

UNITED STATES PATENT OFFICE

CHRISTIAN J. KAISER, OF GREAT FALLS, MONTANA

VENTILATED TOILET BOWL

Application filed December 18, 1928. Serial No. 326,830.

This invention relates to closet bowls and more particularly to devices of this character having means embodied therein for ventilating same.

5 One of the objects of this invention is to provide, in a manner as hereinafter set forth, a device of the aforementioned character having inherent means for thoroughly ventilating the interior of the bowl from beneath the 10 seat portion thereof, and wherein said means will detract in no way from the appearance of the bowl.

Other objects of the invention are to provide, in a manner as hereinafter set forth, a 15 device of the character set forth wherein a bowl, flushing inlet and air vent are provided in one integral piece which will be simple in construction, strong, durable, efficient in its use and which may be manufactured at 20 low cost.

Further objects and advantages of this invention will be apparent from a study of the accompanying drawings, taken in connection with the following specification.

25 In the drawings, wherein like characters of reference designate corresponding parts throughout the several views:—

Figure 1 is a top plan, partly in section, of a bowl constructed in accordance with this invention.

Figure 2 is a bottom sectional plan taken on the line 2—2 of Figure 3.

Figure 3 is a longitudinal section of the bowl wherein same is shown connected to a 35 flushing tank and a vent pipe.

Referring to the drawings in detail, reference character 1 designates the body portion of a closet bowl of the conventional type and which is provided with an outlet passage 2. 40 The upper portion of the bowl 1 is provided, near its rear end, with a water receiving chamber 3 into which water flows from the flushing tank 4 through a conduit 5. At a point below its upper edge the bowl 1 is provided with a substantially annular water conducting channel 6. The channel 6 communicates with the interior of the bowl 1 for its entire length by means of a continuous opening 7 provided by the lip portion 8 of said bowl in connection with the opposed spaced

body portion thereof. Preferably the opening 7 is approximately one-eighth of an inch in width. The channel 6 communicates, at its opposite ends, with the chamber 3 near the forward end of said chamber and on its opposite side. 55

Projecting rearwardly from the chamber 3, the bowl 1 is provided with an integral extension 10. An outlet recess 11 is formed in the extension 10 rearwardly of the water receiving chamber 3. Communicating with the recess 11, on its opposite sides, are a pair of air passages 12 which extend longitudinally through a portion of the upper part of the bowl 1 on opposite sides of the water chamber 3. The passages 12 are formed in the bowl 1 above the horizontal plane of channel 6. On its inner circumference and at the rear thereof, the upper portion of the bowl 1 is provided with an integral arcuate ledge 13 into 65 which the passages 12 extend longitudinally and communicate with the interior of the bowl through spaced openings 14 formed in the lower face of the ledge. A vent pipe 15 communicates with the outlet recess 11 70 through the coupling pipe 16. It will be noted that recess 11 constitutes a common outlet for passages 12. 75

Intermediate the openings 14, the ledge 13 is provided with an integral, downwardly directed tongue 17 which extends below the bottom of chamber 3 and terminates in opposed, spaced relation to the adjacent interior surface of the bowl 1 in a manner to form a discharge opening 18. The tongue 17 80 forms the forward wall of chamber 3 and constitutes a deflector for directing the water which flows through the discharge opening 18 of chamber 3, downwardly against the inner surface of the bowl at the rear thereof. 85

In use the bowl 1 is ventilated through openings 14, passages 12, outlet 11, coupling pipe 16 and vent pipe 15. When the bowl is flushed, the water, entering chamber 3 through pipe 5 from tank 4, is directed downwardly into the bowl through the opening 18 formed between the tongue 17 and the adjacent portion of said bowl. It will, of course, be understood that some of the water which enters chamber 3 passes into the channel 6 90 95 100

which conducts same around the bowl and discharges it in a sheet-like manner through opening 7 against the entire inner surface of said bowl, resulting in a more thoroughly washed bowl than if the water were discharged thereinto through a series of small openings, as is usual.

By this arrangement of the openings 14 and passages 12 it is impossible for the ventilating structure to interfere with the proper functioning of the flushing mechanism, or vice versa. In addition to this, the novel arrangement of the ventilating means renders the openings 14 invisible.

15 It is believed that the many advantages of a closet bowl constructed in accordance with this invention will be readily understood; and although the preferred embodiment of the invention is as illustrated and described, it is 20 to be understood that changes in the details of construction may be had which will fall within the scope of the appended claim.

What I claim is:—

A closet bowl being provided with a water 25 receiving chamber and a water conducting channel communicating with said chamber and the interior of the bowl; an arcuate ledge formed on the interior of said bowl above the horizontal plane of the channel and at the 30 rear thereof and having its opposite ends merging into the adjacent sides of the channel, a water deflecting tongue carried by the ledge intermediate its ends, extending downwardly below the bottom of the chamber at a 35 point forwardly of same, said ledge constituting the forward wall of said chamber, and, in conjunction with the adjacent wall of the bowl, providing an outlet therefrom directly into said bowl, said bowl being further provided with vent passages disposed on opposite sides of the chamber above the horizontal 40 plane of the channel, said passages leading to a common outlet at the rear of the bowl and each having its forward end provided with 45 an elongated vent opening on the under side of the ledge on opposite side of the deflecting tongue.

In testimony whereof, I affix my signature hereto.

50 CHRISTIAN J. KAISER.
